DIE CASTING APPARATUS

Filed Nov. 24, 1924

5 Sheets-Sheet 5

UNITED STATES PATENT OFFICE.

EDWARD HOTTER, OF CHICAGO, ILLINOIS.

DIE-CASTING APPARATUS.

Application filed November 24, 1924. Serial No. 751,779.

This invention relates to die casting apparatus and has for its objects the matters hereinafter described and claimed.

In the accompanying drawings—

5 Fig. 1 is a side view of a die casting apparatus constructed in accordance with my invention;

Fig. 2 is a fragmentary vertical sectional view on the line 2—2 of Fig. 3;

10 Fig. 3 is a top plan view of the apparatus as shown in Fig. 1;

Fig. 4 is a rear view of the device;

Fig. 5 is a side view of the apparatus showing its application to a horizontally 15 arranged side gate machine instead of a center gate machine as shown in the preceding figures; and

Fig. 6 is a top plan view of the parts shown in Fig. 5, with all parts above the 20 die bed omitted for the sake of illustration.

In the drawings, 1 indicates a pot containing molten metal and set in a fire-box 2, as usual in devices of this general character. Upright standards 3, 4 are at the forward 25 and rear ends, respectively, of the fire-box 2. Two horizontal rods 5, 5 extend between the upper ends of these standards and are supported thereby, there being a rod at each side of the apparatus, as shown in Fig. 3.

30 A container 6, in the form of the customary goose-neck, operates in the pot 1 to pick charges of molten metal and discharge the same under pressure into the die 7 located forward of the standards 3, 3, as shown in 35 Figs. 1 and 3. As shown in Fig. 4, upright arms 8, 8 are on opposite sides of the fire-box 2 and have their lower ends fulcrumed by pivot pins 9, 9, in the slot heads of vertically adjustable screws 10, 10. The upper 40 ends of the arms 8, 8 extend inward toward each other over the fire-box 2, and have their inner ends 11, 11 extending downward toward the pot 1, as shown in Fig. 4. These arm ends 11, 11 carry a horizontal cross 45 pin 12, extending through a boss 13 on the container 6. The pin 12 is preferably fitted tight in this boss and its ends are rotatable in the arm ends 11, so that the container is pivotally supported by the arms.

50 The container has a discharge nozzle 14 at its forward end to enter the inlet opening 15 of the die 7, as shown in Fig. 1, the nozzle passing through an enlarged opening 16 in the upright plate 17 secured to the standards 3.

55 By the screws 10, 10, the arms 8 may be

given vertical adjustment to raise and lower the container to adjust its nozzle 14 for proper registration with the inlet opening of the die. Said screws 10, as shown in 60 Fig. 4, pass through slides 18, one for each screw and carried on the outside of the fire-box 2. The slides 18, 18 have grooves to receive horizontal ribs 19, 19 on the outside of the box 2 for horizontal adjustment 65 of the container. To make this adjustment, the slides 18 carry end lugs 20, 20 and in which are tapped screws 21, 21 engaging the ribs, as shown. This adjustment allows for taking up wear on the nozzle and also 70 to make the nozzle properly fit its inlet opening.

Arranged between the rods 5, 5 adjacent their rear ends is a crank shaft 22, having its ends journaled in boxes 23, 23 on the 75 rods 5, 5, as shown in Figs. 3 and 4. These rods at the boxes are threaded to receive clamp nuts 24, 24 for holding the boxes on the rods and providing endwise adjustment thereof when required. Fixed to the crank 80 shaft 22 is a spur gear 25 in mesh with a segmental gear 26 fixed to a short shaft 27 journaled in the box 23 at the gear 25, as shown in Figs. 1 and 3. The hub of the gear 26 is provided with a boss carrying an 85 operating member or rod 28 having a handle at its outer end (Fig. 3) for turning the gear.

The container 6 carries a box 29 at its 90 rear end. Said box is open to receive the forward end of a link 30 pivoted in the box on a horizontal pin 31, as shown in Figs. 3 and 6. Said link 30 carries at its rear end a cross pin 32, on the ends of which are rollers 33, 33 traveling in cam grooves 34, 34 in the uprights 4, 4 at the rear of the device. These grooves are in the inner faces of the uprights and have vertically straight lower ends with the joining portions inclined upwardly and rearwardly, as shown 95 in Fig. 1.

A yoke 35 (Figs. 1 and 4) straddles the link 30 and is pivoted thereto adjacent its rear end by a horizontal pin 36. Said yoke 35 is coupled to the crank portion of the 100 shaft 22 by a connecting rod 37. Said rod 37 is screw-threaded and carries nuts 38, 38 on the opposite side of the yoke for adjustment purposes.

When the parts occupy the positions 110 shown by full lines in Fig. 1, the container 6 has its nozzle 14 in the inlet opening 15

of the die, so that the charge of molten metal in the container may be forced by pressure from the hose 39 into the die. In this position of the parts, the crank portion 6 of the shaft 22 extends vertically downward below the rods 5, 5 at right-angles thereto and, being on center, locks the link 30 against upward movement out of its horizontal position. The rollers 33, 33 at this time are in the vertically straight lower ends of the grooves 34 and hold the link against rearward movement. Thus, the container is held locked in discharging position with its nozzle fitting tight in the inlet opening of the die to avoid leakage and against any movement under the pressure of discharging the metal into the die.

After charging the die, the rod 28 is raised, and by the gears 25, 26 the crank shaft 22 in turning upward lifts the rear end of the link 30 and withdraws the nozzle 14 from the inlet opening of the die as the rollers 33 start up the inclined portions of the cam grooves 34. The lower inclined portions of these grooves meet the vertical lower ends of said grooves just above the aligned horizontal diameters of the rollers 33 and pins 11, 31, and 36 when the link is horizontal as indicated by the line *a* in Figs. 1 and 5. 30 This is what locks the link against endwise movement when the container 6 is discharging.

As soon as raised by the crank 22, the rollers start up the inclined portions of the groove 34 and by the arms 8, 8 swing the container 6 backward to withdraw the nozzle from the inlet opening of the die and free of the plate 17. The continued upward travel of the rollers swings the arms 8 rearward as shown in dotted lines in Fig. 1, and tilts the forward end of the container into the pot 1 for submerging the nozzle 14 in the molten metal for refilling the container by gravity through the nozzle, as indicated by dotted lines in Fig. 1. 45 Moving the rod 28 downward lowers the crank portion of the shaft 22 and swings the container 6 out of the pot 1 on the rods 8, 8. As the rollers 33 travel down the cam grooves 34, the arms 8, 8 are swung forward to their vertical positions to move the nozzle 14 directly into the inlet opening 15 of the die for filling the same with another charge.

As shown in Fig. 1, a set-screw 39 carried by an inwardly extending lug 40 on the box at the gears 25, 26 is arranged in front of the crank portion of the shaft 22 and prevents its being swung beyond center or locking position shown in Fig. 1. This set-screw can be adjusted to stop the action of the shaft when the nozzle 14 comes into proper register with the inlet opening 15.

The uprights 4, 4 have horizontal adjustment on the fire box 2, so that they may be set forward or backward to accord with the 60 horizontal adjustment given to the container

6. To accomplish this, said uprights 4, 4 have horizontal base flanges 41, 41 resting on top of the pot and bars 42, 42 carried by the upright side walls of the fore box 2 along their upper edges, as shown in Fig. 4. T-slots 70 43, 43 are in these bars to receive the heads of holding screws 44, 44 carried by the base flanges 41 and clamped thereto by nuts, as shown in Fig. 4.

To provide for accurate horizontal adjustment of the uprights 4, 4, I provide horizontal screws 45, 45 above the bars 42, 42 and extending through upright lugs 46, 46 on said bars in advance of the members 4, 4, as shown in Figs. 1 and 5. These screws engage upright lugs 47, 47 on the base flanges 41, as shown. To allow for this horizontal adjustment of the member 4, 4, the rods 5, 5 where they extend through the upper ends of said members are threaded and receive adjusting nuts 85 48, 48, as shown.

The rear end of the link 30 may be adjusted laterally to line up the nozzle of the container 6 for proper register with the inlet opening of the die 7. This is accomplished 90 by making the rear of said link bifurcated to receive an adjusting nut 49 on the threaded mid-portion of the cross pin 32, as shown in Figs. 3 and 6.

The link 30 at its forward end carries on 95 opposite sides vertically arranged set-screws 50, 50, which work against the bottom of the box 29 (Fig. 5). Adjusting these screws raises or lowers, as the case may be, the extreme rear end of the link 30 and the nozzle end of the container about the pivot pin 11 to bring the cross pin 32 and the nozzle end of the container 6 in alignment when the parts are in the positions shown in Fig. 1. This allows for proper horizontal line 105 adjustment when fitting another container or replacing a nozzle.

In Figs. 1 and 3, I have shown my die casting apparatus used with a center gate machine. In this type, the die 7 is upright 110 and has its inlet opening 15 in the rear side of the die. This die has two mold members 7^a, 7^b, the former being fixed to the plate 17 and the latter being carried by a slide 51 on horizontal rods, 52, 52, arranged in upper 115 and lower pairs, as shown in Figs. 1 and 3. Any suitable form of mechanism, power or otherwise, may be employed for moving the slide and carrying the die member 7^b into and out of engagement with its co-operating die member 7^a. The power cylinder and its linkage of my copending application Serial No. 671,287, filed October 29, 1923, may be employed for the purpose.

The die members 7^a, 7^b when closed provide a mold cavity between them, as shown. To eject the casting out of the die when the die members are separated, I provide in the slide 51 a pair of vertically arranged shafts 53, 53. These shafts pass through 120

and are fixed to a fixture 54 by set screws 55, 55. This fixture 54, as shown in Figs. 1 to 3 and 5, carries a rack bar 56 given endwise movement by a toothed portion forming a pinion 57 on a shaft 58 extending to one side of the slide 51 and there provided with a handle 59, as shown in Fig. 1.

The inner end of the rack bar 56 carries a yoke 60 fitting in a T-slot in the adjacent end 10 of a bar or member 61 extending through the slide 51 with one end threaded into a push-off plate 62 carrying a plurality of pins 63, which operate against the casting 64 to eject it from the mold cavity when the die is open, 15 as shown in Fig. 3. The push-off plate 62 works in a chamber in a box 65 carried by the slide 51 behind the die member 7^b. As shown in Figs. 1 and 3, the pins 63 slide in this die member. By the yoke 60, the rack bar 56 has detachable connection with the member 61, thus permitting different dies 20 to be connected with the rack bar on changing dies of the machine.

In Figs. 5 and 6, I have shown my apparatus applied to a horizontally arranged side gate machine, wherein the die 66 with its separable mold members 66^a, 66^b are horizontal. The die member 66^a is mounted on a bed plate 67 clamped on upright rods 68, 68. The die member 66^b is carried on the under side of a slide 69, also on said rods and movable thereon to open and close the die, the same as the machine of Figs. 1 to 4. The movable die member 66^b may also be 35 provided with a casting ejector, as heretofore described. At the nozzle 14 of the container 6, the die 66 has an inlet opening 70 in its side.

In Fig. 5, the fire box 2^a has front lugs 40 71, 71 for the adjacent rods 68 in order to tie the apparatus to the die carrying part of the machine. In Fig. 1, the plate 17 is secured to the uprights 3, 3, and is also supported on a ledge 72 on the fire box 2. The rods 51 are supported at one end by this plate 17, as shown, to couple the casting machine with the fire box 2. Except for the changes described, the devices of Figs. 1 to 4 and 5 to 6 operate the same, and like parts 50 are indicated by the same reference characters.

The rollers 33 and grooves 34 in conjunction with the link 30 provide a cam action 55 on the rear of the container 6 in swinging it into and out of engagement with the die and into and out of filling position in the pot 1. This cam action provides an accurate and positive operation of the apparatus and also allows for the automatic locking on 60 swinging the container into engagement with the die.

By the gears 25 and 26, the speed of the apparatus in actuating the container is increased, over the types of devices heretofore 65 made and used. This gear arrangement re-

quires only one handle or operating member for the device, thus simplifying the mechanism and increasing its output, over the multiple-handle machines as now used. Thus with my invention labor costs are reduced by requiring only one operator for each machine instead of a plurality of operators per machine as heretofore.

With the gear drive, the travel of the container 6 is much faster than in machines 75 now used. This stirs up the molten metal in the pot 1 to keep the mixture uniform.

Due to this gear drive requiring only one handle, the apparatus is made easier to operate and moreover provides a minimum 80 amount of travel for the operating member 28 for the full movement of the container 6.

The details of construction and arrangements of parts shown and described may be 85 variously changed and modified without departing from the spirit and scope of my invention.

I claim as my invention:

1. In a die casting apparatus, the combination 90 with a pot and a die having an inlet opening, of a pivotally supported container having a nozzle, and means having a cam action on the container for moving its nozzle end into and out of the inlet opening of the die and for submerging the nozzle end of the container in the molten metal in the pot for charging the container, said means automatically establishing a horizontal line lock for holding the container engaged with 100 the die on the container reaching discharging position.

2. In a die casting apparatus, the combination 105 with a pot and a die having an inlet opening, of a pivotally supported container to the rear of the die and having a nozzle at its forward end, and means to the rear of the container having a cam action on its rear end for moving its nozzle end into and out of the inlet opening of the die and for submerging the nozzle end of the container 110 in the molten metal in the pot for charging the container, said means automatically establishing a horizontal line lock to the rear of the container for holding the same 115 engaged with the die on the container reaching discharging position.

3. In a die casting apparatus, the combination 120 with a pot and a die having an inlet opening, of a pivotally supported container having a nozzle, and means having a cam action on the container for moving its nozzle end into and out of said inlet opening and for submerging the nozzle end of the container in the molten metal in the pot for charging 125 the container, said means having a single operating member connected therewith by meshing gears to increase the speed of actuation of the container.

4. In a die casting apparatus, the combina- 130

tion with a pot and a die having an inlet opening, of a pivotally supported container having a nozzle, and means having a cam action on the container for moving its nozzle end into and out of said inlet opening and for submerging the nozzle end of the container in the molten metal in the pot for charging the container, said means including a crank shaft and a single operating member geared directly to said shaft for operating the same.

5. In a die casting apparatus, the combination with a pot, of a pivotally supported container having a nozzle, and means including a crank and a cam operated link for moving the container into and out of discharging position and for submerging the nozzle end of the container in the molten metal in the pot for charging the container, said crank and link being moved into position at right-angles to each other on the container reaching discharging position to lock the container in said position.

6. In a die casting apparatus, the combination with a pot, of a pivotally supported container therein, an upwardly and rearwardly inclined guide on the support to the rear of said container, a link pivoted to the container and extending rearwardly therefrom and engaging said guide, and means for raising and lowering the rear end of the link.

7. In a die casting apparatus, the combination with a pot, of pivotally supported arms extending above the pot, a container pivotally carried by said arms, and means having a cam action on the container for swinging it with said arms and about the pivotal connection therewith.

8. In a die casting apparatus, the combination with a support and a pot, of upwardly extending arms on opposite sides of the pot and fulcrumed at their lower ends on the support, a container between the arms and pivotally carried thereby in said pot, and means having a cam action on the rear end of the container for moving the same with said arms and about the pivotal connection therewith.

50 9. In a die casting apparatus, the combination with a support and a pot, of upwardly extending arms on opposite sides of the pot and fulcrumed at their lower ends on the support, a container between the arms and pivotally carried thereby in said pot, means on the support to the rear of the pot and having upwardly and rearwardly inclined grooves therein, a link pivoted to the container and extending rearwardly therefrom and working in said grooves, and means for raising and lowering the rear end of said link.

10. In a die casting apparatus, the combination with a support and a pot, of upwardly extending arms on opposite sides of

the pot and fulcrumed at their lower ends on the support, a container between the arms and pivotally carried thereby in said pot, spaced uprights on the support to the rear of the pot and having upwardly and rearwardly inclined grooves therein, a link pivoted to the container and extending rearward therefrom and having rollers in said grooves, and a crank shaft above the link and connected therewith for raising and lowering said link.

11. In a die casting apparatus, the combination with a support and a pot, of a container in the pot and fulcrumed on the support, means to the rear of the pot and having upwardly and rearwardly extending inclined grooves with the lower ends of the grooves vertically straight, a link pivoted to the container and extending rearward therefrom and having rollers in said grooves, and a crank shaft above the link and connected therewith for raising and lowering its rear end, said crank shaft being on center when the rollers are in the lower ends of the grooves for holding the container in discharging position.

12. In a die casting machine, the combination with a pot, of a pivotally supported container working in the pot, cam means to the rear of the container and including a link pivoted to the container and extending rearwardly therefrom, and means for adjusting the link and the container for horizontal alignment thereof when the container reaches discharging position.

13. In a die casting apparatus, the combination with a support and a pot thereon, of upwardly extending arms on opposite sides of the pot and having their lower ends fulcrumed on the support by means permitting horizontal and vertical adjustment of said arms, a container between the upper ends of the arms and pivotally carried thereby in said pot, and means for moving the container with the arms and about the pivotal connection therewith.

14. In a die casting apparatus, the combination with a support and a pot thereon, of a container working in the pot and fulcrumed on the support, an upwardly and rearwardly inclined guide on said support, a slotted box carried at the rear of the container, a link extending into said box and having pivotal connection therewith with the rear end of the link engaging said guide, adjustment screws carried by the link and engaging the bottom of the box for aligning the link horizontally with the forward end of the container, and means for raising and lowering the rear end of the link.

15. In a die casting apparatus, the combination with a support and a pot thereon, of a container working in the pot and fulcrumed on the support, a pair of opposed uprights on the support to the rear of the

pot and having upwardly extending and rearwardly inclined grooves, a link pivoted to the container and extending rearwardly therefrom with the rear end of the link between said uprights, a cross pin carried by the link at its rear end and having rollers in said grooves, and means for raising and lowering the rear end of the link.

16. In a die casting apparatus, the combination with a support and a pot thereon, of a container working in the pot and fulcrumed on the support, a pair of opposed uprights on the support to the rear of the pot and having inwardly opening grooves extending upwardly and inclined rearwardly, a link pivoted to the container and extending rearward therefrom with its rear end between the uprights, a cross pin carried by the link at its rear end and having rollers in said grooves, a nut threaded on said pin and engaging the link for lateral adjustment thereof, and means for raising and lowering the rear end of the link.

17. In a die casting apparatus, the combination with a pivotally supported charge carrying container, of means having a cam action on the container for moving the container into and out of discharging position, said means automatically establishing a positive horizontal line lock for holding the container in discharging position on the container reaching the same.

18. In a die casting apparatus, the combination with a pivotally supported charge carrying container having a discharge nozzle at its front end, of means having a cam action on the rear end of the container for moving the container into and out of discharging position, said means including an operating link pivotally connected to the rear of the container; the link, its pivotal connection with the container, and the nozzle all being brought into horizontal alignment on the container reaching discharging position for holding the same therein.

19. In a die casting apparatus, the combination with a support, of a charge carrying container pivotally mounted thereon and having a discharge nozzle at its forward end, means on the support to the rear of the container and having an upwardly and rearwardly inclined guide with a vertically straight portion at its lower end, and a link pivoted at one end to the rear end of the container and having its other end co-operating with said guide in the movement of the container into and out of discharging position; the link, its pivotal connection with the container, the vertically straight lower end of the guide, and the nozzle all

being brought into horizontal alignment on the container reaching discharging position for holding the same therein.

20. In a die casting apparatus, the combination with a pivotally supported charge carrying container, of means having a cam action on the container and including a link pivoted to the container for moving the same into and out of discharging position, said link being brought into a horizontal position and held from vertical as well as endwise movement on the container reaching discharging position.

21. In a die casting apparatus, the combination with a pivotally supported charge carrying container, of means including a connected link and crank for moving the container into and out of discharging position, said link and crank assuming positions at right-angles to each other on the container reaching discharging position for holding the container therein.

22. In a die casting apparatus, the combination with a pot, of a charge carrying container disposed in said pot, and a pair of upwardly extending pivotally supported arms on opposite sides of the container and having pivotal connection therewith for supporting the container in the pot, said arms allowing the container to be swung rearward out of discharging position and at the same time be dipped into the pot for charging.

23. In a die casting apparatus, the combination with a support, of a pot associated therewith, a charge carrying container disposed in said pot, and a pair of arms outside the pot and on opposite sides of the same, said arms having their lower ends pivoted to the support and having their upper ends extending above the pot and pivoted to the container for supporting the same in said pot, said arms allowing the container to be swung rearward and downward from discharging position and at the same time be dipped into the pot for charging.

24. In a die casting apparatus, the combination with a support, of a charge carrying container associated therewith, a pair of arms on opposite sides of the container and having pivotal connection therewith for supporting the same, and means providing a pivotal connection between the arms and support and enabling vertical and lateral adjustment to be given to the arms.

In testimony that I claim the foregoing as my invention, I affix my signature, this 18th day of November, 1924.

EDWARD HOTTER.
